DENTIFRICE DISPENSER

Jay Doblin, Chicago, Ill., assignor to Lever Brothers Company, New York, N.Y., a corporation of Maine

Filed Feb. 7, 1966, Ser. No. 958

Term of patent 14 years

(Cl. D4—3)

FIG.1.

FIG.2.

FIG.3.

FIG.4.

FIG.5.

I claim:

The ornamental design for a dentifrice dispenser, as shown.
